HANGER FOR SUPPORTING AND FIXING THE POSITION OF A CORD

Yasha Heifetz, Rte. 81, Clinton, Conn.

Filed Dec. 30, 1963, Ser. No. 77,969

Term of patent 3½ years

(Cl. D54—1)

FIG 2

FIG 3

FIG 4

FIG 5

FIG 1

FIG 6

FIG. 10

FIG. 8

FIG. 9

FIG. 11

FIG. 7

FIG. 12

FIG. 1 is a bottom perspective view of a hanger for supporting and fixing the position of a cord and showing my new design;

FIG. 2 is a side elevation view of the hanger of FIG. 1;

FIG. 3 is a front elevation view of the hanger of FIG. 1;

FIG. 4 is a sectional view of the hanger of FIG. 1 taken on line 4—4 of FIG. 3;

FIG. 5 is a top plan view of the hanger of FIG. 1;

FIG. 6 is a bottom plan view of the hanger of FIG. 1;

FIG. 7 is a bottom perspective view of a modified form of a hanger for supporting and fixing the position of a cord;

FIG. 8 is a side elevation view of the hanger of FIG. 7;

FIG. 9 is a sectional view of the hanger of FIG. 7 taken on line 9—9 of FIG. 10;

FIG. 10 is a front elevation view of the hanger of FIG. 7;

FIG. 11 is a top plan view of the hanger of FIG. 7; and

FIG. 12 is a bottom plan view of the hanger of FIG. 7. The broken line showing in FIGS. 2 and 8 is for illustrative purposes only.

I claim:

The ornamental design for a hanger for supporting and fixing the position of a cord, as shown.
